[57] **CLAIM**

The ornamental design for the "birdhouse", as shown.

DESCRIPTION

FIG. 1 is a front elevational view of a birdhouse showing my new design;

FIG. 2 is a left side elevational view thereof;

FIG. 3 is a rear elevational view thereof;

FIG. 4 is a bottom plan view thereof;

FIG. 5 is a top plan view thereof;

FIG. 6 is a front perspective view thereof;

FIG. 7 is a front phantom view thereof;

FIG. 8 is a front elevational view of a second embodiment of FIG. 1;

FIG. 9 is a side elevational view of FIG. 8;

FIG. 10 is a bottom plan view of FIG. 8;

FIG. 11 is a top plan view of FIG. 8; and,

FIG. 12 is a rear elevational view of FIG. 8.

The broken lines are for purposes of illustration only and form no part of the claimed invention.
